(57) CLAIM

The ornamental design for a pen case, as shown and described.

DESCRIPTION

FIG. 1 is a front view of a pen case showing my new design;

FIG. 2 is a rear view thereof;

FIG. 3 is a left side view thereof;

FIG. 4 is a right side view thereof;

FIG. 5 is a plan view thereof;

FIG. 6 is a bottom view thereof;

FIG. 7 is a front view which is in the unfolded state of a pen case of FIG. 1;

FIG. 8 is a rear view of a pen case of FIG. 7;

FIG. 9 is a left view of a pen case of FIG. 7;

FIG. 10 is a right view of a pen case of FIG. 7;

FIG. 11 is a plan view of a pen case of FIG. 7; and,

FIG. 12 is a bottom view of a pen case of FIG. 7.

The broken lines shown are included for the purpose of illustrating the unclaimed portions of and form no part of the claimed design.
